UNITED STATES PATENT OFFICE

COLEMAN LINDZEY NICHOLSON, 2d, OF SYRACUSE, NEW YORK, ASSIGNOR TO PASS & SEYMOUR, INC., OF SOLVAY, NEW YORK, A CORPORATION OF NEW YORK

LAMP RECEPTACLE

Application filed August 13, 1928. Serial No. 299,418.

This invention relates to incandescent lamp receptacles or sockets, and more particularly to such receptacles as are used for illuminating signs.

5 It is a general object of the present invention to provide a novel and improved article of manufacture comprising a sign receptacle and a temporary closure for the contact recess therein.

10 One of the features of the invention comprises the arrangement of a temporary closure disk at the mouth of the recess in a lamp receptacle which is adapted to receive the base of an incandescent lamp, said closure being arranged in the receptacle at the factory and being readily removable when it is no longer required.

Another feature of the invention comprises the arrangement of a closure means in the 20 mouth of the recess of a lamp receptacle, which means may be provided with indicia or advertising or used for other purposes.

Other and further features and objects of the invention will be more apparent to those 25 skilled in the art upon a consideration of the accompanying drawing and following specification, wherein is disclosed a single exemplary embodiment of the invention, with the understanding, however, that such changes 30 may be made therein as fall within the scope of the appended claims without departing from the spirit of the invention.

In said drawing:

Figure 1 is a face view of a portion of an 35 electric sign having incorporated therein receptacles provided with the present invention; and

Figure 2 is a vertical section taken on line 2—2 of Fig. 1.

40 In the manufacture of electric signs, and particularly those large outdoor signs used for display advertising, it is customary to form the outline of the letter, figure or the like from a metal plate or sheet which is perforated where each lamp is to be inserted. Behind each perforation is secured a suitable lamp receptacle attached to the metal plate in any desired manner, as by screws or the like. There is usually a flange on the receptacle which passes through the perforation in

the metal plate to accurately locate the receptacle and to prevent the screw contact of the lamp base from coming in contact with the metal plate. The work of assembling the receptacles on the plate and wiring them into the various electric circuits is such that it is not convenient to paint the face of the sign plate until this work is completed, for fear of damaging the paint. When painting the face of 55 the sign plate with the receptacles assembled thereon, there is grave danger of paint being splashed into or otherwise entering the receptacles, where it may cover either the screw shell or the center contact thereof, or both, to such an extent as to prevent suitable electrical contact between the lamp base and these contacts. Paint on the screw shell contacts may 60 make it difficult to place the lamps in position. Further, such paint may harden after 70 the lamps are in place and make it almost impossible to remove them. The present invention contemplates overcoming all these difficulties in a simple manner. It adds no appreciable cost to the receptacles and requires no 75 appreciable additional work on the part of the electricians assembling the sign. Furthermore it allows the painters to work more rapidly, since they do not have to make any attempt to prevent the entrance of paint into 80 the receptacles.

Referring to the drawing, there is disclosed at 10 a section of a metal plate such as forms the main portion of a sign. It is provided with circular perforations 11 at suitable intervals to receive electric lamps to form the various letters, figures or the like. To receive and provide the electrical contact for the various lamps, a receptacle such as 12 is arranged at each perforation. The receptacle shown in the drawing is of conventional form, of which there are a number, and it is not intended that the present invention be limited to this particular form of receptacle.

90 As shown, the receptacle comprises an irregularly shaped block 13 of insulating material, for instance porcelain, having the extending arms 14 adapted to receive the screws 95 15 passed through suitable perforations in 100

the sign plate adjacent the main perforation and serving to hold the receptacle tightly against the back face of the sign plate. The circumferential flange 16 formed integral with the insulating block projects through the main perforation 11, as shown, to prevent accidental contact of the lamp base screw contact with the metal plate 10. The receptacle block 18 is provided with the cylindrical recess 17 which extends up through the flange 16 and opens on the front face of the block at 18. Within this recess is arranged the conventional screw shell contact 19 and at the bottom of the recess is the center contact 20. The outer edge of the screw shell contact is well within the recess 17 in the insulation block, as best shown in Fig. 2.

The main feature of the invention consists in the closure means 21 which is assembled in the receptacle at the factory or before mounting the receptacles on the sign plate. This closure means 21 is arranged in the mouth of the recess of the receptacle. Conveniently the closure means 21 may take the form of a paper or cardboard disk of such a diameter that its edges may tightly engage the wall of the recess 17 when it is pressed into position, as shown in Fig. 2. The outer edge of the screw shell contact 19 forms a convenient stop to prevent the closure from being pressed too far into the receptacle.

If desired, the closure member may have printed thereon any suitable indicia, such as the name of the manufacturer of the socket, facts concerning the capacity of the socket or a legend telling how to remove the closure etc. The disk is of sufficient rigidity so that ordinary engagement of a paint brush in painting over the face of the sign will not press it further into the receptacle and cause its seal with the edges of the recess to be broken. After the sign is painted, these closure disks can readily be removed by the workmen inserting the lamps into the receptacle. Being of paper or like material, they can be readily punched in at one side with the finger and then withdrawn, or a suitable implement may be used for this purpose.

The invention in its many aspects provides an extremely convenient closure means for sign receptacles which requires no additional labor on the part of the electricians assembling the sign and which gives absolute protection to the contacts against paint applied either with a brush or a spray gun, and which can be readily removed by workmen inserting the lamps with but slight additional labor and which insures adequate protection for the contacts as well as provides a convenient means for advertising the manufacturer or jobber selling the receptacles.

Having thus described the invention, what

is claimed as new and desired to be secured by Letters Patent is:

1. In a lamp receptacle having an insulation block provided with a recess, a screw shell contact in said recess below the mouth thereof and a removable disk frictionally engaging the wall of said recess near the mouth to retain the disk in position and sealing the recess to protect the contact. 70

2. In a lamp receptacle having an insulation block provided with a recess, a screw shell contact in said recess below the mouth thereof and a disk frictionally engaging the wall of said recess near the mouth to retain the disk in position and sealing the recess to 75 protect the contact, said disk resting against the outer edge of said contact. 80

In testimony whereof I hereunto affix my signature.

COLEMAN L. NICHOLSON, II.
